UNITED STATES PATENT OFFICE.

BARNES NEVILLE WALLIS, OF WESTMINSTER, LONDON, ENGLAND, ASSIGNOR TO AIRSHIP GUARANTEE COMPANY, LIMITED, OF WESTMINSTER, ENGLAND, A BRITISH COMPANY.

LIGHTER-THAN-AIR AIRCRAFT.

Application filed August 20, 1927, Serial No. 214,342, and in Great Britain October 12, 1926.

This invention relates to lighter-than-air aircraft, (hereinafter termed airships).

The gas bags of airships are fitted with a safety valve adapted to open automatically 5 when the gas pressure in the bag rises above a predetermined amount and it has been proposed to locate the automatic valve at the bottom of the gas bag within the lower end of a tubular gas trunk extending through 10 the interior of the gas bag, the valve being adapted to open at blowing pressure so as to allow gas to enter the gas trunk and the trunk having an outlet at its upper end for the escape of lifting gas.

According to the present invention the 15 automatic gas valve or valves is or are located at or towards the bottom of the gas bag within the lower end of a tubular gas trunk, attached to the gas bag. Preferably 20 the said gas valve or valves is or are attached to the exterior of the gas bag and lie in a pocket or recess in one of the sides or flat ends of the gas bag so that the valve or valves is or are positioned between a pair 25 of contiguous gas bags and enclosed within a light gas-tight casing which surrounds the same and which casing opens at its upper end into a trunk or uptake shaft of suitable shape leading from the gas valve or valves 30 to the top of the bag.

In order that the said invention may be 35 clearly understood and readily carried into effect the same will now be described more fully with reference to the accompanying drawings which illustrate more or less diagrammatically and by way of example only one embodiment of the present invention, and in which:—

Figure 1 is an end view of a portion of 40 the gas bag of an airship fitted with a gas-tight trunk and an automatic gas discharge valve located within a gas-tight casing constructed according to the present invention.

Figure 2 is a sectional elevation and Figure 3 is a sectional plan view of Figure 1.

Figure 4 is a detail view showing on an enlarged scale a portion of the gas discharge trunk, and

Figure 5 is a sectional plan view of Figure 4.

Figure 6 is a three quarter perspective view of the lower portion of the gas trunk and the gas-tight casing or cage fitted with twin automatic gas valves, the cage having 55 a hinged air valve adapted to break any

syphonic action that may be set up in the gas trunk, the gas valves and the air valve being shown in the closed position.

Figure 7 is a sectional view through the casing or cage showing in full lines the gas 60 valves in their open position, and in dotted lines the open position of the air valve.

Figure 8 is a view on an enlarged scale showing one method of attaching the gas trunk and cage to the gas bag, and Figures 65 9 and 10 are detail views showing a method of sealing the gas bag that may be adopted when it is desired to remove the gas valve.

1 is the gas trunk; 2 is the gas-tight casing or cage at the lower end thereof for 70 accommodating the automatic gas valves. 3 is the recess in the end of the gas bag A for accommodating the gas trunk and the cage 2, and 4, 4 are patches for connecting the trunk, as also the cage 2, to the gas bag 75 A. The recess 3 is provided not only for the purpose of accommodating the gas trunk 1 and the cage 2 but also to allow the gas bag A to fit snugly against the radial or bulk-head wiring B disposed between the bag 80 A and the contiguous gas bag C, the recess 3 being formed by cutting away the material of the gas bag at a point which, in the example shown, is situated to the left of the centre A' of the gas bag A. The trunk 85

1 is in communication with the atmosphere at its upper end and is built up of horizontally arranged D-shaped frames 1^a, 1^a spaced apart by vertically disposed wires 1^b, 1^b, and at its lower end it is connected to the cage 2, 90 the latter being constituted by a light metal framework 2^a strengthened by bracing wires 2^b, both the trunk 1 and the cage 2 being covered with gas-tight or relatively gas-tight fabric 1^c and 2^c. In the example illustrated a portion of each gas bag A and C towards the lower end thereof is cut away 95 at D to form a corridor extending lengthwise of the ship.

5, 5 are the twin automatic gas valves 100 which are fastened to necks on the gas bag A and supported by the cage 2. 6 is the hinged air valve adapted to open automatically and to break any syphonic action set up in the gas trunk 1. In view of the aforesaid arrangement the gas trunk and the casing are free to follow the undulations of the gas bag in its lower part when the latter becomes deflated.

Referring to Figures 8, 9 and 10 the ma- 110

aterial of the gas bag A is continued as shown at a to form an outwardly projecting circular neck and the fabric 1^e of the gas trunk as also the fabric 2^e of the cage 2 are continued inwardly so as also to form an inwardly projecting circular neck 1^d . a', a' are bands which are tightened around the valve body 5 outside both the fabric necks a and 1^d , thus gripping the fabric necks to the valve 5 and securing the parts firmly in position. The valve body 5 is formed with corrugations 5^a for the reception of the bands a', a' . a^2 is a collapsed portion of the said neck a forming a concertina like arrangement. Normally the portion a^2 is held in the collapsed position by stitching a^3 and the inner band a' . Should, however, it be desired to remove the valve 5 from the gas bag the stitching a^3 is cut as shown at Figure 9. Thereafter the collapsed portion is expanded and by passing a cord around the expanded neck the gas bag can be cut off from the valve and the valve removed without permitting any of the lifting gas to escape.

In previous constructions where it was proposed to locate the valve at the bottom of the bag so that it opened into a trunk located between a pair of contiguous gas bags dangerous leakages of gas were liable to take place along the bottom of the airship owing to the fact that a positive connection between the valve and the gas trunk leading to the top of the airship was not provided and the valve was merely held frictionally and in more or less accurate coincidence with the inlet leading to the uptake shaft. In the present arrangement, however, the valves 5, 5 are enclosed within a gas-tight casing 2 which surrounds the gas valves and which positively connects it to and holds it in accurate coincidence with, the inlet A^2 in the bag A leading to the gas valves 5, 5.

Furthermore and in previous constructions where the valve was located between contiguous gas bags there was also a liability for syphonic action to set up in the gas trunk and the lifting gas to be thereby wasted, but by means of the valve 6, syphonic action in the uptake shaft or gas trunk is prevented. Instead of a flap valve such as 6 which is hinged at its lower end to the cage 2 a clack valve may be provided consisting of a disc of rubber or other suitable flexible material covering an aperture or a series of apertures in the bottom or lower wall of the casing which surrounds the automatic valve or valves, the clack valve being retained on its seat, for example, by means of a small central disc and stud. Owing to this arrangement, and in the event of hydrogen being discharged by the automatic valve or valves in such quantities as to produce a super-pressure within the gas-tight

casing and the trunk, the valve 6 will remain closed under the influence of gravity assisted by the super-pressure of gas on its upper side. Consequently, the trunk 1 will be maintained gas-tight during the discharge of hydrogen in large quantities. If however, the pressure within the gas trunk 1 falls below that of the surrounding atmosphere the valve 6 will open automatically and admit air to the trunk so as to restore the pressure balance, thus avoiding syphonic action and allowing the automatic gas valves 5, 5 to close. The provision of a valve constructed and arranged as above described also serves to equalize any sub-pressure which may be experienced in the uptake shaft or gas trunk 1 as a result of aerodynamic suction in pitched flight, thus preventing any leakage of hydrogen which would otherwise be caused by the suction produced under these conditions although the gas bag itself might not be fully inflated.

What I claim and desire to secure by Letters Patent of the United States is:—

1. A gas bag for an airship having means for permitting the escape of gas comprising in combination a gas trunk located between said gas bag and an adjacent gas bag and attached at intervals along its length to said gas bag, and at least one valve in said gas bag, said gas trunk fitting in a gas-tight manner over said valve.

2. A gas bag for an airship having means for permitting the escape of gas comprising in combination a gas trunk located between said gas bag and an adjacent gas bag and attached at intervals along its length to said gas bag, a gas-tight casing with which said gas trunk communicates and at least one valve in said gas bag opening into said casing.

3. A gas bag for an airship having means for permitting the escape of gas comprising in combination a gas trunk located in a recess in said gas bag and between said gas bag and an adjacent gas bag and attached at intervals along its length to said gas bag, and at least one valve in said gas bag, said gas trunk fitting in a gas tight manner over said valve.

4. A gas bag for an airship having means for permitting escape of gas comprising in combination a gas trunk located between said gas bag and an adjacent gas bag and attached at intervals along its length to said gas bag, a gas-tight casing with which said gas trunk communicates, an air valve associated with said casing and adapted to open automatically under sub-pressure conditions and at least one valve in said gas bag opening into said casing.

5. A gas bag for an airship having means for permitting the escape of gas comprising in combination a gas trunk located between

said gas bag and an adjacent gas bag and attached at intervals along its length to said gas bag, an air valve communicating with said gas trunk and adapted to open 5 automatically under sub-pressure conditions and at least one valve in said gas bag, said gas trunk fitting in a gas-tight manner over said valve.

6. An airship having gas bags each provided with means for permitting the escape 10 of gas comprising in combination a gas trunk located between each of said gas bags and attached at intervals along its length to one of said gas bags, and at least one 15 valve in each of said gas bags, said gas

trunks fitting respectively in a gas-tight manner over said valves.

7. An airship having gas bags each provided with means for permitting the escape 20 of gas comprising in combination a gas trunk located between each of said gas bags and attached at intervals along its length to one of said gas bags, an air valve communicating with each of said gas trunks and adapted to open automatically under 25 sub-pressure conditions and at least one valve in each of said gas bags, said gas trunks fitting respectively in a gas-tight manner over said valves.

BARNES NEVILLE WALLIS.
